UNITED STATES PATENT OFFICE

CARL CHRISTIAN LARSEN, OF COPENHAGEN, DENMARK

SORTING SCREEN

Application filed June 20, 1929. Serial No. 372,362, and in Denmark November 2, 1928.

The present invention relates to sorting screens of the kind using co-axial discs rotating on a plurality of parallel shafts, and is mainly characterized in that the discs on consecutive shafts are displaced relatively to each other in such a manner that the discs on one shaft, in the intervals between the discs on the adjoining shafts, will reach nearly all the way out to these shafts. When at the same time the discs are made polygonal, for instance triangular, so as to give them sharp corners, an excellent automatic cleaning of the sorting screen is effected, since the neighbouring discs engaging the spaces between the discs will constantly cause any pinched pieces of the material being sorted to be struck loose and transported away.

One construction of a sorting screen with adjustable discs constructed in this manner is illustrated on the drawing, where

Fig. 1 shows a portion of the screen in side elevation with the limiting side wall removed,

Fig. 2 a partial vertical cross-section of a portion of the screen, and

Fig. 3 a detail.

The screen is supported by girders 1 which in not shown manner support limiting side plates 2 and on which supporting bearings 4 are provided for the mutually parallel shafts 3 which outside of one of the limiting plates 2 support overhanging sprocket wheels 6, which in not further detailed manner are all maintained in synchronous rotation. On the shafts fixed discs 7 are provided and sliding discs 8 between the former.

In the construction shown these discs are shaped as equilateral triangles and are disposed in such a manner on each shaft that their edges are all mutually parallel. The discs on any two adjacent shafts, on the other hand, are turned about 15° relatively to each other, as shown by Fig. 1, so that the corners do not pass the horizontal plane simultaneously. The discs are further staggered relatively to each other, and are of such a size that the points on one disc can nearly reach both neighbouring shafts, each disc projecting into the space between two of the discs provided on each of these shafts.

By giving the discs this shape and disposing them in this manner various advantages are attained which are of importance to the operation of the sorting screen. The advantage is attained, for instance, that pieces of the material to be sorted, which during the work become pinched between two adjacent discs will instantaneously and automatically be struck loose by the neighbouring disc engaging the space between the two discs concerned, so that any clogging of the screen is entirely precluded. Then the relatively sharp corners have a good transporting effect on the material to be sorted. By turning the discs on two consecutive shafts about 15° relatively to each other a wavelike motion of the material is attained, so that not the entire material has to be lifted at a time, whereby the operation of the sorter would become quite irregular, and at the same time the advantage is attained that the angle A between the edges of consecutive discs will be larger, so that any pinching effect between these sides will be better avoided than if these angles were smaller.

In the construction shown the shafts 3 are mainly solid, although at one end they are fitted with a bore 16 for a sliding rod 17 the free end of which projecting beyond the shaft 3 is threaded. The threaded end of the rod 17 supports a handwheel 18 fitted with an interior groove 19 engaging a flange 20 on the end of the shaft 3, in such a manner that the hand-wheel may be turned relatively to the shaft 3 but cannot be moved axially in relation thereto. The rod 17 supports at its inner end a transverse rod 21 projecting through slots 22 in the shaft 3. The projecting ends of the transverse rod 21 are connected to a ring 23 adapted to slide on the shaft 3 and supporting three bars 24 which are parallel to the shaft 3 and extend through the hubs 25 and 26, respectively, of the fixed discs 7 and the sliding discs 8. The bars 24 pass smoothly through holes in the hubs 25 of the fixed discs, but in a manner not shown in detail they are connected to the hubs 26 of the sliding discs, so that the latter will follow the motion of the bars 24.

The adjusting device acts in the following manner:

When the hand-wheel 18 is turned on the end of the shaft 3 then the rod 17 and, thereby, the ring 23 will be displaced in axial direction relatively to the shaft 3. Hereby the bars 24 and the sliding discs 8 will also be displaced axially, in such a manner that the space *b* between a sliding disc 8 and a fixed disc 7 may be reduced from the size shown in Fig. 2 to the size *a* which is produced when the sliding disc, as indicated by dotted lines in the figure, is situated midways between two consecutive fixed discs 7.

By this adjusting device the advantage is attained that the size of grain of the screened material may be varied inside of certain limits.

It is preferable to be able to lock the hand-wheel 18 relatively to the shaft 3, in such a manner that no undesired mutual rotation of these parts may occur accidentally. Such a locking device is not shown on the drawing.

What I claim as new is:

Sorting screen comprising a plurality of parallel shafts, supporting co-axial fixed and movable discs longitudinally of the shafts in alternate succession, said discs displaced in such a manner relatively to each other that the discs on one shaft, in the space between the discs on the neighbouring shafts can extend nearly up to said shafts and means for simultaneously adjusting the movable discs longitudinally on their shafts.

In testimony whereof I affix my signature.
CARL CHRISTIAN LARSEN.
